UNITED STATES PATENT OFFICE.

WILLIAM McCANSE, OF DURANT, OKLAHOMA.

INCINERATOR.

1,238,034.

Specification of Letters Patent. Patented Aug. 21, 1917.

Application filed October 23, 1916. Serial No. 127,189.

To all whom it may concern:

Be it known that I, WILLIAM McCANSE, a citizen of the United States, residing at Durant, in the county of Bryan and State of 5 Oklahoma, have invented certain new and useful Improvements in Incinerators, of which the following is a specification.

This invention relates to incinerators, or apparatus for burning refuse, garbage, etc., and has for one object the provision of a compactly arranged structure in which the refuse may be deposited and will be rapidly and thoroughly consumed. Another object of the invention is to provide novel means 10 for supplying air under forced draft to the incinerating chamber and also to heat the said air before it enters the incinerating chamber. A still further object of the invention is to provide a structure in which 15 fire will be applied directly on to the matter to be consumed and also below the same, yet another object of the invention being to provide means whereby obnoxious and harmful odors will be eliminated before the 20 smoke passes into the chimney.

The invention also has for its object the provision of an apparatus for the stated purposes which may be easily repaired and from which the ashes may be easily removed. Other incidental objects will appear as the description of the invention 25 proceeds.

The invention is illustrated in the accompanying drawings, in which:

30 Figure 1 is a front elevation of an apparatus embodying my improvements;

Fig. 2 is a side elevation of the same;

Fig. 3 is a vertical longitudinal section;

Fig. 4 is a transverse section on the line 40 4—4 of Fig. 3;

Fig. 5 is a plan view of the deck floor;

Fig. 6 is a horizontal section on the line 45 6—6 of Fig. 3;

Fig. 7 is a horizontal section on the line 7—7 of Fig. 3;

Fig. 8 is a detail transverse section taken on the line 8—8 of Fig. 2;

Fig. 9 is a detail transverse section on the line 9—9 of Fig. 3.

50 In carrying out my invention, I provide a foundation 1 of concrete and it is to be understood that the dimensions of the same

will be determined by the size of the plant to be erected. Upon this foundation 1, I 55 erect a shell 2 which will preferably be circular in plan view and which will be constructed of metal reinforced by angle iron 3 at such places as may seem desirable in any particular instance. Above the shell 2 is a deck or floor 4 of reinforced concrete supported upon and spaced from the shell by beams 5, as will be readily understood, the beams being so disposed as to furnish a firm support for the entire concrete deck or floor and at the same time provide an air space 60 through which atmospheric air may circulate freely. This deck or floor 4 will be of such dimensions as will permit loaded vehicles to drive over the same and dump their contents directly into the incinerating 65 chamber, it being understood that the entire furnace may be located below the grade of the street or road, or inclined ways may be provided leading from the street or road to the dumping floor or deck 4. At the sides 70 of the dumping deck or floor, I provide railings 6 which will serve as guards to prevent the teams or operators falling over the sides of the deck and being thereby injured, said railings being shown only in Fig. 1 as 75 they are not a part of my present invention.

The incinerator is constructed with an arched roof 7 over the incinerating or cremating chamber and between the said roof and the metallic shell 2 is placed a filler 85 consisting of a base or bottom portion 8 of asbestos and a top portion 9 of cinders, a concrete binder 10 being arranged between the asbestos and the cinders and extending from the roof to the shell 2. The metallic 90 shell 2 fits around the body of the furnace without being secured thereto so that the expansion and contraction of the different parts will be accommodated and rupture of the structure from unequal expansion 95 and contraction of adjoining connected parts will be avoided. In the apex of the arched roof 7 is an opening through which the material to be treated is dumped, the said opening being defined by a ring or 100 hopper 11 of fire brick having an annular upstanding rim 12 extending into the frame of the dumping deck or floor 4 and it may be noted at this point that all parts of the

furnace or passage-ways which are exposed to the direct action of heat will be constructed of fire brick of first class quality. A cover seats upon the upper edge of the 5 rim 12 so as to close the feed opening and this cover consists of a fire brick body 13 held together by a metallic cap 14 extending over the entire upper surface of the said body and having an annular depending rim 10 or flange which engages and fits closely around the edge of the said fire brick body 13. This cover is connected by bolts 15 with an outer metallic cap 16 provided with an eye 17 which may be engaged by a hook 18 on a chain 19 running over pulleys 20 and 21 carried by a crane 22 erected on the dumping deck or floor in such position that the hook may be easily brought into engagement with the eye 17 and the chain then manipulated so as to lift the cover. In most cases the cover will be very heavy so that it will tend to seat properly by the force of gravity and also so that it will be enabled to withstand the intense heat to which 25 the structure is subjected when in use. By setting up the crane upon the dumping deck or floor the lifting of the cover may be accomplished very readily without placing upon the operator excessive manual strain. 30 In operation the loaded wagons are driven on to the deck and halted at such position as to bring their dumping ends into position adjacent the hopper or feed opening after which the cover is raised. The wagon is 35 then dumped, the cover replaced and the wagon may be drawn off to gather another load. For convenience, the crane and its attachments are shown only in Fig. 1 as they may be of any well known construction 40 and form no part of this invention. The furnace or incinerator is constructed with a base or lower floor 23 which may rest directly upon the foundation 1, the said floor and the foundation being so shaped as to 45 provide an ash pit 24 resting directly upon the foundation 1 and a duct or passage-way 25 in rear of and separated from said ash pit extending under the furnace and communicating, as will be presently set forth, 50 with the chimney. A main floor 26 is also provided above the floor 23 and is spaced therefrom and supported from the walls of the furnace and also by a baffle wall 27 extending between the two floors at a point 55 preferably near the center of the main body of the furnace. The baffle wall 27 extends vertically across a duct or passage leading rearwardly from the fire box 28 arranged above the ash pit 24, and the floor of this 60 duct or passage is depressed at about the center of the furnace, as shown at 29. This duct or passage-way receives liquid matter fed into the incinerating chamber and retains the same in position to be ex-

posed to the direct action of the fire in the 65 fire-box 28 so that it will be evaporated. I will, therefore, hereafter refer to this duct or passage as an evaporating pit. The upper floor 26 is constructed with a depressed portion 30, providing an ash pit 31, and a 70 fire box 32 is provided above said ash pit, the grate bars 33 of both fire boxes being supported by the front wall of the structure and the upper edges of the inner or rear ends of the depressed portions of the respective 75 floors. Openings 34 are provided through the upper floor 26 at various points to facilitate the escape of liquid matter into the evaporating pit and at the center of said floor is a large opening 35 which is covered 80 by a dome-shaped grate 36 through which the liquid matter may escape to the evaporating pit and heat and flame from the pit may arise to the incinerating chamber, it being noted that the baffle wall 27 is so disposed that its front surface merges into the under surface of the said dome-shaped grate. In rear of the baffle wall 27 and aligned with the fire-box 28 is a duct or passage-way 37 leading into a vertical flue 38 85 which is in communication with the chimney. In the side walls of the main body of the structure are vertical escape flues 39 opening at their upper ends into the incinerating chamber, as shown at 40, and 90 having their lower ends opening directly into transverse passages 41 which communicate with the evaporating pit in front of the baffle wall and also have branch passages 42 leading into the passage 37 through 100 openings or spaces 43. The passages 41, 42 and 37 form direct extensions of and outlets for the chamber which is in front of the baffle wall as will be readily noted and the evaporating pit may therefore be said to extend 105 around the baffle wall. An opening or flue 44 leads through the rear wall of the incinerating chamber above the floor 26 and opens directly into the flue 38, as clearly shown. A damper 45 of fire clay or other 110 refractory material is slidably mounted in vertical ways 46 formed in the wall of the furnace and this damper may extend across the flue 44 or across the flue 37 as may be desired. To guard against collapse of the 115 damper in the event of its cracking, I secure around the edge of the same a metallic ring 47. A cable 48 leads upwardly from the said damper and is extended forwardly over the filling 9 and below the deck 4 and then 120 depends in front of the furnace to carry a counterweight 49 so that the damper may be shifted easily and will remain in the position in which it is set. It will be readily understood that if this damper be lowered 125 the draft through the incinerating chamber will be conducted through the flue 44 to the vertical rear flue 38 and, consequently, es-

cape directly from the upper incinerating chamber, but if the damper be raised the circulation will be indirect and will be deflected through the openings 40 into the 5 flues or passages 39, 41 and 42 to the passage 37 which is in communication with the lower end of the flue 38.

The flue 38 receives the gases generated in the operation of the apparatus and said 10 gases will rise to the upper end of said flue and will be thoroughly commingled and consumed for which reason this flue 38 will be hereafter referred to as the mixing and settling chamber. The front of the said chamber is defined by the rear wall of the furnace at its lower end and by a wall 50 erected outside the shell 2 in its upper portion, the sides of the chamber being defined by side walls 51 and the rear of the chamber being 20 defined by a baffle wall 52 which terminates short of the roof 53 of the chamber. An open space is thus provided above the baffle wall 52 through which the gases and products of combustion may enter a preheating 25 chamber 54, the rear wall 55 of the said chamber being connected with the outlet flue 56 leading to the chimney (not shown). A damper 57 is provided within the flue 56 and this damper is carried by a cable 58 30 which extends up to and through the space between the shell 2 and the deck 4, being then carried down in front of the furnace to support a counter-weight 59 whereby the damper may be easily opened or closed and 35 be held in the position in which it is set. It will also be readily noted that the positions of the counter-weights 49 and 59 will indicate to the attendant the positions of the dampers to which they are respectively 40 attached so that it will not be necessary for the attendant to travel around the furnace or to open the same in order to inform himself as to the adjustment of the dampers.

Within the preheating chamber 54 is a 45 metallic drum or shell comprising a lower rectangular body portion 60 which is in contact with the front and rear walls of the chamber, but is spaced from the sides of the same. Above the said rectangular portion 50 60 is a laterally flared portion 61 which merges into an upper portion 65 which extends to the side walls of the chamber, the flared portion 61 providing open spaces 63 at the corners of the chamber through which 55 the gases may flow. The flared portion of the preheater is also upwardly tapered and merges into the upper portion or narrow flue 65 which has its ends against the side walls of the chamber 54 but has its front 60 and rear walls spaced from the rear of the said chamber and from the baffle wall 52. The upper end of the flue 65 enters a header or air box 66 which is arranged over the chamber 38 and the preheating chamber 54,

as shown. The chamber 38 is provided with 65 a clean-out door 67 adjacent its bottom and clean-out doors 68 are provided at the bottom of the preheating chamber 54. Upon the side of the header or air box 66 is mounted a fan or blower 69 which is in communication with the interior of the header at one side and at another point is in communication with a conduit 70 leading over the furnace and delivering into a header 71 at the front of the furnace over the fire boxes. 70 The fan or blower 69 may be driven by any convenient means and is illustrated in the present drawings as connected by a belt 72 with an electric motor 73, the motor forming no part of the present invention and being shown in a conventional manner. From the front header 71 a plurality of flues or conduits extend downwardly, as shown most clearly in Figs. 1 and 2, the flow through these conduits or flues being regulated by 80 valves or dampers 74 of any convenient or preferred construction. The front flues 75 and 76 extend downwardly at the sides of the fire boxes and open respectively into the ash pits 31 and 24, as shown. The rear 90 flues or conduits 77 and 78 are turned rearwardly at their lower ends and enter the evaporating pit and incinerating chamber respectively. The initial supply of air is drawn through a conduit 79 extending 95 through the filling 9 and leading from the open air space below the deck or dumping floor 4 into a space or chamber 80 which is provided over the top of the fire box and under the header 71. From the said upper 100 space or chamber 80 similar spaces or chambers 81 extend downwardly along the sides of the fire boxes and between the same and the flues 75, 76, 77 and 78. The lower ends of these side chambers 81 discharge directly 105 into air passages 82 which extend rearwardly through the foundation and discharge into the duct or passage 25, as shown at 83.

Clean-out doors 84 are provided at the 110 lower ends of the vertical passages 39 and stoking doors 85 are provided at various points around the incinerating chamber. Adjacent the clean-out doors 84, pits 86 are constructed in the ground and these pits 115 are normally covered by doors 87. They are of proper dimensions to accommodate the ash bucket 87' which is suspended from a trolley 88 mounted upon a track 89 extending around the structure so that the ash bucket may be readily brought into position adjacent any clean-out door to receive the ashes which may be readily withdrawn from the incinerating chamber or from the ash pits below the fire boxes. The track 89 may 120 be carried to any point of discharge so that the ashes and cinders may be very readily removed and disposed of. The track and 125

trolley may be of any well-known construction and are shown only in a conventional manner.

The fire boxes and ash pits are, of course, provided with the usual doors to permit the insertion of fuel and removal of the ashes, but the nature of the fuel is immaterial and oil or gas may be utilized by equipping the furnace with the proper burners.

10 In the operation of my improved apparatus, air is drawn through the supply conduit 79 and flows therefrom through the upper chamber 80 and side chambers 81 to the duct 25. From the said duct the air rises through the preheater to the header 66 whence it is drawn by the fan 69 and forced through the conduit 70 into the header 71 from which it passes under pressure through the several flues 75, 76, 77 and 78. It being understood 15 that a fire is kindled in the fire box 28 or 32, the air delivered into the ash pit below the said fire box will rise through the fire and quickly bring the same to the desired degree of combustion so that the temperature within 20 the apparatus will be rapidly raised. The hot air from the fire passes through the evaporating pit or the incinerating chamber to the settling and mixing chamber 38 where the gases arising from the burning of the refuse will be thoroughly commingled and consumed, the product rising to the top 25 of said chamber and flowing over the baffle wall 52 to the space between the same and the front side of the flue 65 of the preheater, 30 the said flue deflecting the heated gas and air downwardly so that they will be forced to flow through the spaces 63 at the front of the preheater and at the bottom of the chamber 54. These heated currents will then 35 flow rearwardly below the tapered portion 61 of the preheater and at the sides of the lower extremity 60 of the same and then rise through spaces 63 at the rear of the same to escape through the flue 56 to the chimney, 40 it being noted that the preheater acts as a baffle for the products flowing from chamber 38. This tortuous circulation of these gases will obviously retard their escape and permit the solids therein to settle to the bottom 45 of the mixing and preheating chambers so that when they finally reach the chimney they will be devoid of obnoxious odors and of injurious particles. It will be obvious that as these gases escape from the incinerating chamber and the evaporating pit they will be highly heated and will impart heat 50 to the walls of the flue 65 so that the air rising through the preheater and said flue will be heated and, consequently, the air delivered to the furnaces and to the incinerating chamber and the evaporating pit from the front header will be sufficiently heated 55 to prevent cooling of the fire boxes, the evaporating pit or the incinerating chamber. 60 The desired temperature therefore in the 65

working chambers may be maintained with a very economical consumption of fuel. As the flue 65 becomes heated it reacts so as to radiate heat which aids in the destruction of deleterious elements of the gases flowing 70 from the settling and mixing chamber.

The front and rear walls of the flue 65 rising through the preheating chamber and the shells defining the air spaces 80 and 81 will be secured in position by rivets or 75 bolts 90.

When the material to be burned is wet or contains a large percentage of liquid matter, a fire should be established before charging the incinerating chamber so as to bring 80 the temperature of said chamber up to the working degree, but when the refuse is dry or comparatively free of liquid matter the heat from preceding burnings will suffice to start the operation. By providing two fires, 85 one playing directly on the refuse or the upper portion of the same and the other working below the refuse, the highest possible consuming capacity is attained and the refuse or other matter is very quickly reduced 90 and destroyed. If the fire clay damper 45 be raised so that the heated currents cannot escape directly from the incinerating chamber, said currents will be forced to pass into the flues 39, 41, and 42 and thence through 95 the flue 37 into the chamber 38. This travel of these currents will expose them to the direct action of the lower fire so that the combustible particles will be further burned before passing to the settling and mixing 100 chamber. To escape from said chamber the gases are obliged to rise to the top of the same and will, consequently, be commingled and burned and all dust will settle to the bottom of the settling and preheating chambers 105 so that the smoke escaping from the chimney will be free of odors. The stoking doors 85 may be utilized for the removal of ashes from the incinerating chamber and the evaporating pit is readily accessible at 110 all times for the same purpose. The form of the several chambers is such that little stoking will be required and the removal of ashes can be accomplished while the plant 115 is in operation.

Repairs may be very easily made. If it be necessary to renew the arch over the incinerating chamber the deck over the same may be raised by the use of jacks and the filler then removed, thereby providing access to the arch. The old arch may then be broken up and removed and the new arch built after which the filler is replaced and the deck lowered into its normal position. The rivets or bolts connecting the jacket 120 around the fire and ash boxes are arranged with the nuts on the outer sides of the jacket so that they may be readily removed when 125 repairs are needed in this part of the apparatus. The dome-shaped grate 36 at the 130

center of the incinerating chamber and over the evaporating pit may be replaced at any time when the temperature is low enough to permit.

5 Having thus described the invention, what is claimed as new is:

1. In an apparatus for the purpose set forth, the combination of an incinerating chamber having a central opening in its

10 floor, an escape flue leading from the rear of said chamber, an evaporating pit disposed below the incinerating chamber, an escape flue leading from the evaporating pit, a dome-shaped grate disposed over the opening

15 in the floor of the incinerating chamber, a baffle wall in the evaporating pit having its front surface merging into the under surface of the grate, means for establishing communication between the incinerating chamber and the evaporating pit at the sides

20 of the same, and superposed fire boxes at the front of and in communication with the incinerating chamber and the evaporating pit respectively.

25 2. In an apparatus for the purpose set forth, the combination of an incinerating chamber, an evaporating pit disposed below said chamber, superposed escape flues leading from the chamber and the pit respectively,

30 laterally disposed flues establishing communication between the pit and the chamber, means for supplying heat to the chamber and to the pit, and a single means common to both escape flues whereby as one escape flue is closed the other flue will be opened to control the circulation through the chamber and the pit.

35 3. In an apparatus for the purpose set forth, the combination of an incinerating chamber, an evaporating pit below the incinerating chamber, means for establishing communication between the chamber and the pit through the floor of the chamber, escape flues leading respectively from the incinerating chamber and the evaporating pit,

40 a baffle wall extending vertically between the floors of the incinerating chamber and the evaporating pit, flues at the sides of the incinerating chamber and the evaporating pit having lateral branches opening respectively into the incinerating chamber and the evaporating pit in advance of and at the sides of the baffle wall and also establishing communication with the escape flue leading

45 from the evaporating pit in rear of said baffle wall, means for supplying heat to the incinerating chamber and the evaporating pit, and a single means common to both escape flues for closing either escape flue and thereby opening the other escape flue.

50 4. In an apparatus for the purpose set forth, the combination of a compartment in which refuse may be treated, a fire box opening into said compartment, an air chamber over

said chamber and having one end open to the atmosphere, chambers leading downwardly from the first-mentioned chamber at the sides of the fire box, a duct under the said compartment leading rearwardly from the fire box and in communication with the air chambers at the sides of the same, means for heating the air escaping from said duct, and means for delivering the heated air into the fire box and the said compartment.

70 5. In an apparatus for the purpose set forth, the combination of a compartment in which refuse may be treated, a fire box opening into said compartment, an air intake above the fire box, an air chamber over

75 the fire box into which said air intake discharges, air chambers at the sides of the fire box leading downwardly from the first-mentioned chamber, a duct leading rearwardly from the said air chambers at the

80 sides of the fire box, a preheater at the rear end of said duct and communicating therewith, a header into which the upper end of

85 said preheater opens, a second header disposed above the fire box and the first-mentioned air chamber, flues leading from the

90 said second header to the fire box and the compartment respectively, and means for drawing the air from the first-mentioned header and forcing it into the second header.

95 6. In an apparatus for the purpose set forth, the combination of a compartment in which refuse may be treated, a fire box opening into said compartment, an air intake passage leading over the fire box and down at the sides of the same and then rearwardly under the said compartment, a settling and mixing chamber in rear of the compartment and in communication therewith to receive escaping heated gases therefrom, a

100 preheating chamber in communication with said settling and mixing chamber, a preheater disposed in said chamber and having its lower end in communication with the air

105 passage under the said compartment, said preheater being expanded laterally above its lower end to bear against the side walls of the preheating chamber and contracted from front to rear to form a baffle spaced

110 from the front and rear walls of the same, and means for drawing air from said preheater and delivering the same under pressure to the fire box and the compartment in

115 which refuse is treated.

7. An apparatus for the purpose set forth comprising a circular incinerating chamber having an arched roof and having a central opening in its floor, a circular arched grate resting upon the floor at the edge of said opening and extending over the same, an

120 evaporating pit below the incinerating chamber, superposed fire boxes opening into the front of the incinerating chamber and the evaporating pit respectively, superposed escape flues leading from the rear of the in-

125 130

cinerating chamber and evaporating pit respectively, a settling and mixing chamber in communication with both the escape flues, a preheater chamber in communication with 5 the settling and mixing chamber, a preheater in the preheater chamber constituting a baffle for the products flowing therefrom, an air inlet duct opening into the lower end of said preheater, and means for 10 positively drawing air from the upper end of said preheater and delivering it to the superposed fire boxes and to the incinerating chamber and the evaporating pit.

8. An apparatus for the purpose set forth 15 comprising an evaporating pit, a baffle wall across the same, lateral passages leading from the front of said baffle wall, an escape flue in rear of said baffle wall in communication with said lateral passages, an 20 incinerating chamber above the evaporating pit and the said passages and escape flue, an escape flue leading from the incinerating chamber, flues leading down the sides of the incinerating chamber to the said lateral pas-

sages, and superposed fire boxes opening 25 into the incinerating chamber and evaporating pit respectively.

9. An apparatus for the purpose set forth comprising an evaporating pit, an incinerating chamber above said pit, fire boxes at the front of and opening into the incinerating chamber and evaporating pit, a preheater exposed to the heated products flowing from the evaporating pit and incinerating chamber, an air chamber over the fire boxes in 30 communication with the atmosphere, air chambers at the sides of the fire boxes in communication with the first-mentioned air chamber, a duct connecting said chambers with the lower end of the preheater, a header over the first-mentioned air chamber, means for delivering air from the preheater to the 35 said header, and means for delivering the air from the header to the fire boxes and to the incinerating chamber and the evaporating pit.

In testimony whereof I affix my signature.

WILLIAM McCANSE. [L. s.]
